UNITED STATES PATENT OFFICE.

FRANK H. BUTTS, OF MINNEAPOLIS, MINNESOTA.

MEANS FOR UTILIZING RADIATED HEAT OF BOILERS.

SPECIFICATION forming part of Letters Patent No. 409,915, dated August 27, 1889.

Application filed May 6, 1889. Serial No. 309,767. (No model.)

To all whom it may concern:

Be it known that I, FRANK H. BUTTS, of Minneapolis, in the county of Hennepin and State of Minnesota, have invented certain 5 new and useful Improvements in Means for Utilizing the Radiated Heat of Steam-Boilers, of which the following is a specification.

My invention relates to steam-boilers of usual form and arrangement; and its object is 10 to utilize the heat radiated from the boiler-front and breeching and base of smoke-stack in warming the air drawn into the fire-box, and also to diminish the temperature of the boiler-room; and it consists, generally, in the 15 construction and combination hereinafter described, and particularly pointed out in the claims.

With a boiler of ordinary construction and arrangement the heat radiated from it makes 20 the temperature of the boiler-room at times almost unbearable, and a large amount of heat is wasted. By the use of my improvement this waste heat is thoroughly utilized in warming the air taken in at the draft-doors 25 to assist combustion, and the excessive temperature of the boiler-room is reduced, so that even in hot weather it is not uncomfortable for the firemen, even in close proximity to the boiler. I accomplish this result by inclosing 30 the heated radiating-surfaces of the boiler and its attachments in a jacket or case, through which the air is conveyed to the fire-box, taking up the radiated heat and carrying it into the fire-box, the air being prefer- 35 ably taken from the upper part of the boiler-room.

In the drawings forming part of this specification, Figure 1 is a longitudinal vertical section of a boiler fitted with my improve- 40 ment. Fig. 2 is a sectional view of same on line $x-x$ of Fig. 1, and Fig. 3 is a front elevation of same.

In the drawings, 2 represents the boiler having the flues 3; 4, the fire-box underneath 45 the same; 5, the ash-pit having the draft-openings 7.

9 is the smoke-flue having the check-damper 10. Entirely surrounding the smoke-flue and boiler-front is the jacket or casing 50 11, preferably of sheet-iron, and provided with suitable doors 8 and 13, opening, respectively, to the fire-box and ash-pit doors, and to the door 12 in front of the boiler-flues, for the purpose of giving access to these parts. Ar- 55 ranged in the wall of the jacket, preferably

at as high a point as possible, is a suitable air-inlet 16, having the door 14. This door is preferably hinged and provided with a suitable lifting cord or chain 15, running over suitable sheaves 17 and 18, and hanging down 60 in convenient reach from the floor of the room.

Any suitable means of securing it may be employed to hold the door 14 open to any desired extent to control the inflow of air. The air entering the opening 16 passes around and 65 over the heated surfaces of the smoke-flue or breeching, thence downward over the boiler-front, and into the draft-openings to the fire. The air, being taken from the upper part of the room, thus carries off the excess of heat 70 in the room, and the jacket is kept comparatively cool, so that no discomfort is experienced from being in close proximity to the boiler, and the air taken into the fire-box to assist the combustion is at a high tempera- 75 ture, whereby a material economizing of fuel is attained. By means of the outer doors 8 and 13 convenient access is afforded to the different parts of the boiler.

I claim as my invention—

1. The combination, with a steam-boiler, of a casing surrounding and inclosing the front of the boiler and its fire-box and ash-pit doors, and the uptake or smoke-pipe of the same, with a continuous air-space between said casing and said surfaces having communication with the fire-box of the boiler, and an inlet for the outer air arranged at or near the top of said casing, whereby the air taken into the fire-box is received from the upper part of 85 the boiler-room and conducted over the heated surfaces of the boiler directly to the draft-opening, substantially as and for the purposes set forth.

2. The combination, with a steam-boiler, of 90 the casing 11, inclosing the smoke-pipe and boiler-front, with a continuous air-space between the same communicating with the ash-pit, and the air-inlet 16, arranged in the upper part of said casing, provided with the 95 door 14, and the doors 8 and 13, arranged in said casing and allowing access to the fire-box and ash-pit doors and boiler-front, substan- 100 tially as described.

In testimony whereof I hereunto set my hand this 1st day of May, 1889.

FRANK H. BUTTS.

In presence of—

A. M. GASKILL,
BESSIE BOOTH.
